UNITED STATES PATENT OFFICE.

WILLIAM F. LEONARD, OF COLUMBUS, OHIO.

ELEVATOR.

SPECIFICATION forming part of Letters Patent No. 680,871, dated August 20, 1901.

Application filed June 7, 1900. Serial No. 19,438. (No model.)

To all whom it may concern:

Be it known that I, WILLIAM F. LEONARD, a citizen of the United States, residing at Columbus, in the county of Franklin and State 5 of Ohio, have invented certain new and useful Improvements in Elevators; and I do hereby declare the following to be a full, clear, and exact description of the invention, such as will enable others skilled in the art to 10 which it appertains to make and use the same.

The object of this invention is to provide simplified and economical mechanism for automatically opening and closing the doors at elevator-landings.

15 The invention consists in the parts and combinations of parts hereinafter described, and pointed out in the claims.

In the accompanying drawings, showing an embodiment of the invention, Figure 1 is a 20 view in elevation of a car broken out horizontally, equipped with the mechanism, some parts being omitted for the sake of clearness. Fig. 2 is a view of the door with its closing-weight. Fig. 3 is a plan view of the mechanism on the car for winding up the door-opening weight, with the coöperating devices on the car and shaft for releasing said door-opening weight when the car stops at a landing. Fig. 4 is a side view looking toward the 30 right of Fig. 1, the edge of the well at the landing being also shown. Fig. 5 is a detail perspective of the device for releasing an opened door when the car starts away from the landing.

35 1 designates the car. Journalized horizontally under the floor of the car is a shaft 2, loose on which is a rope-winding drum 3, and fixed on which is a bevel pinion or gear 4. The drum has a laterally-projecting pin 3^a. The bevel-gear 4 engages a larger gear 5, supported in a suitable bracket or frame 5^a, Fig. 1. Sliding vertically in the axis of the gear 5, but rotating with the said gear, is a shaft 6, having in its lower end a grooved collar 6^a, 45 engaged by the shortarms of ordinary weight-ed governor-levers 7. The upper end of the shaft 6 is furnished with a grooved collar 6^b, that is engaged by the inner arm of a double crank-shaft 8, journaled at the under side of 50 the car. Mounted under the car is a cam-slide 9, having cams 9^a and 9^b, (see also dot-

ted lines, Fig. 2,) that keep the pivoted finger 10 in the shaft 2 in or out of position to engage or to be disengaged from the pin 3^a on the drum 3, according to the position of 55 the slide. If the slide is in, the end of the finger is kept disengaged from the pin 3^a by the cam-surface 9^a, and if the slide is out the pin is held by the cam-surface 9^b in position to engage the pin 3^a. Attached to the drum 60 is one end of a cord 11, that passes over pulleys 12 and 12^a near the top of the car and has on its other end a weight 13. This cord 11 passes through an eye on an arm 9^c, hinged to the slide 9, and on the cord, on opposite 65 sides of the eye, are stops 11^a and 11^b, that shift the slide in and out when the cord has been wound or unwound from the drum to the proper extent, as hereinafter set forth. The cord 11 also has a button 11^c, that is 70 caught by a spring-catch 14 when the cord is wound up to the proper extent. The catch 14 has a trigger 14^a, that projects beyond the face of the car.

Hinged in the elevator-well near each of 75 the several landings is a plate 15, that can be moved by the outer end of the cranked shaft 8 when the latter is actuated by the shaft 6 to move the catch 14 and release the button 11^c. The cord 11 is also furnished with a pin 80 11^d, that projects horizontally through a slot in a horizontal runway 16 along the top of the car. The lower side of the runway 16 is cut away at 16^a, so that the pin 11^c can be pulled down, as hereinafter set forth. 85

Sliding vertically on the front of the car is a jointed rod 17, having a hook 17^a at its upper end. The lower end of this rod 17 is connected eccentrically to a motor-controlling device 18, so that if the motor-controller is 90 operated to move the car either up or down the shaft or well the rod 17 is pulled down.

The door 20 is the usual sliding door and has a weight 20^a for closing it. The door also has a catch 21 on the movable part of a toggle-frame 21^a, secured to the door, the said hook engaging when the door is closed a catch 22 in the shaft or well. The weight 13 on the car is sufficiently heavier than the weight 20^a to open the door when the weight 100 13 acts on the door.

Extending vertically in the well is a fixed

rope 23, on which works a pulley 3^b, fast on the outer end of the shaft 2. As the car moves up or down the shaft the frictional contact of the rope and pulley rotate the shaft 2. A small pulley 24 on the car to make a bend in the rope, and therefore to insure and increase the frictional contact of the rope and pulley, as well understood, can be employed.

- 10 The operation is as follows: Let it be supposed that the weight 13 is down, the door open, and the car about to be started from one landing to another. In this state of facts the slide 9 and the stop 11^b are in their outer 15 position and the cord entirely unwound from the drum 3. Further, the end of the longer arm of the finger 10 will be in position (if the shaft 3 be rotated) to strike the pin 3^a on the drum and carry the drum with the rotation 20 of the shaft 2. When the car is started, the shaft 2 is rotated, and with said shaft the drum 3 will also be rotated and the cord 11 wound up thereon until the stop 11^a pulls the slide 9 in. When the slide is pulled in, 25 the cam 9^a disengages the finger 10 from the pin 3^a and the winding operation ceases; but slightly before the finger is so disengaged from the pin 3^a the button 11^c has passed below the catch 14, and the weight 13 is thus held 30 suspended. When the motor-controller is operated to give motion to the car, as before stated, the jointed rod 17 is pulled down, thus pulling the pin 11^d, which at that time is directly under the hook 17^a, as shown in 35 Fig. 5, down and away from the frame 21^a and allowing the weight 20^a to close the door. The door, however, closes before the car moves away any considerable distance. When the car is in motion, the governor-balls are also 40 in motion and the shaft 6 pulled down. When the shaft 6 is down, the outer end of the crank-shaft 8 is not in position to act on the plate 15 at any of the landings; but when the car stops at or near a landing the governor-balls drop and depress the outer part of the 45 crank-shaft against the plate 15, which being moved throws the latch 14 off the button 11^c, thus allowing the weight 13 to fall and open the door, as before indicated. The operation of the winding device and the opening and closing apparatus is the same whether 50 the car is to move up or down the well, except that the shaft 2 is turned in one direction going down and in the opposite direction going up. It will thus be observed that 55 both the opening and closing of the door are entirely automatic and are respectively effected simply by the usual operation of the motor-controller in stopping at and starting 60 from any landing.

The several parts herein shown and described can of course be modified to some extent without departing from the scope of the invention. As one illustration of this I 65 would suggest that a spring in the place of the weight 20^a could be employed; but I pre-

fer to use a weight, because of the uniformity and noiselessness of its action.

What I claim, and desire to secure by Letters Patent, is—

70 1. In combination, an elevator shaft or well, a car to move therein, a door to said shaft, a weight to close the door, and a preponderating weight on the car to open the same adapted to be automatically brought 75 into action when the car stops opposite the door.

2. In combination, an elevator shaft or well, a car to move therein, a door to said shaft, a weight to close the same, a preponderating weight on the car to open the same, 80 means for automatically causing said weight to open the door when the car arrives and stops opposite the door, and means for automatically restoring said weight to its operative position when the car moves from the door.

3. In combination, an elevator shaft or well, a car to move therein, a door to said shaft, a weight to close the door, a preponderating weight on the car to open the door, 90 means for automatically causing said weight to open the door, when the car arrives and stops opposite the door, and means on the car for automatically restoring said weight to its 95 operative position when the car moves from the door.

4. In combination, an elevator shaft or well, a car to move therein, a door to said shaft, a latch for said door and a weight to 100 close the door, a preponderating weight on the car to open the door, means for automatically causing said weight to release said latch and open said door when the car arrives and stops opposite the door.

5. In combination, an elevator shaft or well, a car to move therein, a door to said shaft, a latch for the door and a weight to close the door, a preponderating weight on the car to open the door, means for automatically causing said weight to release said latch and open said door when the car arrives and stops opposite the door, and means for automatically restoring said weight to its operative position.

105 6. In combination, an elevator shaft or well, a car to move therein, a door to said shaft, a weight to close the door, and a preponderating weight on the car for opening said door, a weight-elevating, and a weight-releasing mechanism on the car adapted to be operated by the motion and cessation of motion, respectively, of the car.

7. In combination, an elevator shaft or well, a car to move therein, a door to said shaft, a weight to close the door, and a preponderating weight for opening the door, a mechanism for elevating said preponderating weight operated by the motion of the car, and a mechanism for releasing said weight 120 operated by the cessation of motion of said car.

8. In combination, an elevator shaft or

well, a car to move therein, a door to said shaft, a weight to close the door, a preponderating weight for opening the door and holding the same open, means operated by the operation of the motor-controller for releasing the door from the preponderating weight.

9. In combination, an elevator shaft or well, a car to move therein, a door to said shaft, a weight to close the door, a preponderating weight for opening the door and holding the same open, means for automatically winding up said preponderating weight,

means for automatically releasing said preponderating weight when the car arrives and stops opposite the door, and means operated by the operation of the motor-controller for releasing the door from the preponderating weight.

In testimony whereof I affix my signature in presence of two witnesses.

WILLIAM F. LEONARD.
